R. L. WIDNEY.

POULTRY COOP.

APPLICATION FILED AUG. 9, 1907.

Patented Oct. 20, 1908.

UNITED STATES PATENT OFFICE.

RALPH L. WIDNEY, OF LA HARPE, ILLINOIS.

POULTRY-COOP.

No. 901,406.

Specification of Letters Patent.

Patented Oct. 20, 1908.

Application filed August 9, 1907. Serial No. 387,890.

To all whom it may concern:

Be it known that I, RALPH L. WIDNEY, a citizen of the United States, residing at La Harpe, in the county of Hancock and State of Illinois, have invented a new and useful Poultry-Coop, of which the following is a specification.

This invention relates to a coop for poultry, more especially to that type of coops used for breeding purposes.

One object of the invention is to provide a coop made preferably of metal of cylindrical form with a removable bottom and ventilating top. The body of the coop is, by choice, made of several sections of sheet metal joined by double lock connections which enable the parts to be separated and packed closer for shipping. The doors, of which there are several, rotate on a single pivot bolt attached to one of the sections.

A further object of the invention is to simplify the construction and utilize the greatest space with the least length of side walls which is possible in a circular structure in which there are no corners; to enable the cleaning of the coop a simple matter; and to provide ample ventilation.

With these and other objects in view the invention consists of the novel construction, combination and arrangement of parts hereinafter described and definitely claimed.

In the accompanying drawing:—Figure 1 is a perspective view of the improved coop, Fig. 2 is a horizontal sectional view of the coop on a plane passing through the doors, Fig. 3 is a vertical sectional view through one side of the coop. Fig. 4 is a detail view illustrating the inner door from within the coop. Fig. 5 is a detail perspective view showing the separation of the body sections. Fig. 6 is a vertical sectional view of a portion of the wall and roof of the coop showing the ventilating space between the top of the wall and the roof.

Similar reference numerals are used for the same parts on all the figures.

The body 1 of the coop is, in this instance, made of three curved sections 2, 3 and 4 which, when joined together by the double lock connections 5, fitting one another endwise, form a circular body for the coop. A coop of this shape affords the greatest space for the amount of material employed and entirely eliminates corners into which young chicks are inclined to crowd and be killed.

Near the bottom edge of the coop is formed

a circumferential bead 6 projecting into the coop, on which the floor 7 partly rests. The body of the coop from the bead 6 to its lower edge is cut vertically at short distances apart into narrow fingers, each alternate finger 8 is then bent inwardly to a horizontal position as an additional support for the bottom 7. The remaining fingers 9 are left standing to support the coop and raise the bottom above the ground that a circulation of air may flow through the spaces 10 under the coop and keep the bottom dry. The floor 7 is of circular shape but appears irregular because of the necessity of enlarging the lock connections 5 to show them clearly.

Above the body of the coop 1 is placed a conical roof 11 the eaves of which extend some distance away from the coop. The roof 11 is raised above the upper edge of the coop by means of metal strips 12 attached to the under side of the roof, bent to form hooks which catch over the edge of the body and leave a space between the roof 13 and the body for ventilating the coop. In one section, say 2, of the coop is cut an opening 14 for the fowls to pass in and out. Pivoted on a bolt at one edge of the opening are two outer doors 14 and 15 and an inner door 16, concentrically curved with the coop and with one another. The outer doors are vermin proof, one, 14, being of wire netting and the other, 15, of solid sheet metal. One or the other of these doors are closed at night to prevent the entrance of rats, weasels, minks and other small animals. They are pivoted centrally on one side of the door and coop opening and have a guard 17 at the other side so that either door can be turned on its pivot and leave the other in place. By shaping and pivoting the doors in the manner described they will, when opened, lie close to the coop and be out of the way. Within the coop is the third door 16 centrally pivoted at one side which enables it to be opened and closed like the outer ones. The inner door is made with a very coarse mesh, the openings being about two inches by four inches. When this door is closed and the others opened, the mother-hen will be kept within the coop but the chicks can pass in and out through the meshes of the door 16. The pivot pin on which the doors turn is necessarily a loose fit so that the curved doors may swing from a closed to an open position and vice

versa. Besides, there is but a single pivot and the doors themselves will spring or yield as their ends pass by the curved side of the coop.

5. A coop made of sheet metal, preferably galvanized iron, may be kept thoroughly clean and sanitary; there are no corners into which dirt can collect, as the corner formed by the walls and bottom is eliminated as soon as the bottom is removed. The parts can then be thoroughly washed and disinfected.

Having described the invention what is claimed is:-

15. 1. A poultry coop comprising a circular body made entirely of sheet metal in separable sections and having a circumferential bead near the bottom edge of said body, spaced fingers extending downwardly from said bead to support the coop above the ground, alternating fingers bent inwardly, and a floor for said coop resting on said bead and the inwardly turned fingers.

2. A coop formed of sheet metal, and a removable floor therefor, the body of said coop having fingers on the lower edge and a horizontal bead above said fingers, said floor supported on the bead and a plurality of said fingers turned inwardly.

30. 3. A coop formed of sheet metal having an inwardly projecting bead and inwardly

turned fingers near its lower end, and a removable floor supported on said bead and fingers.

4. A coop comprising a body, a roof, and 35 hooks secured to and depending from the roof for detachably engaging the upper edge of the body, said hooks constituting means for spacing the roof from the body.

5. A coop comprising a circular sheet 40 metal body, a floor detachably supported within the body, a roof, and combined spacing and supporting means depending from the roof for detachably engaging the upper edge of the body.

45. 6. A knockdown coop comprising a circular body consisting of detachably connected sheet metal sections, a floor detachably supported and surrounded by said sections, a roof, and combined spacing and supporting 50 devices depending from the roof and embracing and detachably engaging the upper edge of the body, said roof extending beyond the wall of the body.

In testimony that I claim the foregoing as 55 my own, I have hereto affixed my signature in the presence of two witnesses.

RALPH L. WIDNEY.
